Bob Pritchel.

UNITED STATES PATENT OFFICE.

HUBERT R. SCHMIDT, OF SWEDESBORO, NEW JERSEY, ASSIGNOR TO FERDINAND D. FLEMING, OF PHILADELPHIA, PENNSYLVANIA.

LATCH NEEDLE.

Application filed June 30, 1927. Serial No. 202,501.

The object of my invention is to provide a needle that is adapted for use in repairing a "run" in a stocking or other knitted fabric. Such ravelings or runs can be, and long have been, repaired by means of ordinary latch needles like those used in knitting machines, but the operation is more or less difficult due to the necessity of carefully controlling the operation of the pivoted latch by preventing its untimely closing against the free end of the hook and by opening it at the proper time. By means of my improved needle, the free end of the latch is maintained spaced from the free end of the hook except when forced thereagainst at that stage of the loop forming operation at which it is necessary to close it, the latch opening automatically at the proper time in the sequence of operations.

My improved needle comprises a shank, hook and latch, all of ordinary form, but combined with a spring that allows the latch to swing freely, from a pendent position, upward throughout nearly the whole arc of nearly 180 degrees required to bring it into contact with the needle hook, but which yieldingly resists such swinging movement of the latch as it approaches the needle hook.

The invention is capable of embodiment in different forms, several of which are shown in the drawings, in which—

Fig. 1 is a side view of a needle embodying my invention and secured in a handle.

Fig. 2 is a plan view of a blank from which said needle is made.

Fig. 3 is a view, similar to Fig. 1, but on an enlarged scale, of the latch end of said needle.

Fig. 4 is a view, similar to Fig. 3, of a modification.

Fig. 5 is a view, similar to Figs. 3 and 4, of another modification.

The needle comprises a shank *a*, an end hook *b* and a pivoted latch *c*. A spring *d* is so positioned that, as the latch is swung toward the hook, the latch engages the spring and is thereby normally prevented from closing against the hook, the spring, however, being compressible to allow the closing of the latch when the thread slides thereover and forcibly presses against it at one stage of the loop forming operation.

In Fig. 2 is shown a blank from which the needle is formed. The blank is widened at *w*; and after the blank is folded longitudinally upon itself to form the completed shank, the

latch *c* is pivotally mounted between the opposing wings of the shank at the widened part thereof. In this widened part *w* of the blank, adjacent to and just above the pivot of the latch, the metal of the blank is slit along two longitudinally extending lines, as at *y*, to form a narrow strip, the upper end of which is severed from the blank, thereby forming a flexible and elastic narrow strip integrally connected at its lower end with the blank. When the blank is folded upon itself longitudinally to form the completed shank, this strip functions as a leaf spring *d*, its free end engaging the latch *c*, in the closing movement thereof, before the latch contacts with the free end of the hook *b*; the spring also functioning to automatically open the latch when it is not held closed by the thread of the fabric.

It is also possible to form a strip as described and sever the lower end of the strip from the blank, thereby forming a leaf spring *e* which is integral with the shank at the upper end of the spring, as shown in Fig. 4, its lower free end being adapted to engage the latch and yieldingly resist its closing movement.

In Fig. 5 the spring is formed by cutting the blank as described, leaving both ends unsevered, and bending in the strip to form a bow spring *f*, which operates in the same manner as springs *d* and *e*.

For hand operation, for which the needle is more particularly intended and adapted, the needle shank is inserted securely in a handle *h*.

Except for the provision of the described spring, operating as described, the needle may exactly conform in structure to that of the ordinary knitting machine needle such as is commonly employed in the fabrication of hose and other knitted goods.

The operation of the described needle, in the repairing of runs in knitted fabric, is the same as that of an ordinary needle when operated, in the manner well known in the art, to close runs; but the spring-opposed latch enables the operation to be conducted with greater facility and speed and with the exercise of less skill.

Having now fully described my invention, what I claim and desire to protect by Letters Patent is:

1. A. needle comprising a shank, an end hook, and a latch pivotally mounted on the

- shank, the latch being of such length that when swung against the hook it extends beyond the extremity of the same, the metal of the shank being slit near the latch pivot to 5 form a leaf spring adapted to engage the latch as it is swung toward the hook and yieldingly oppose its movement into contact therewith and tending, when the latch is closed to open it.
- 10 2. A needle comprising a shank, an end hook, and a latch pivotally mounted on the shank, the metal of the shank being slit along lines from a point in proximity to the pivot of the latch upward toward the hook and cut 15 away from the metal of the shank at one end to form a leaf spring integrally united at one end to the metal of the shank, the free end of the spring extending inwardly and adapted to engage the latch when swung upward toward the hook and yieldingly oppose its 20

movement into contact with the hook and tending, when the latch is closed against the hook, to open it.

3. A needle comprising a shank, an end hook, and a latch pivotally mounted on the shank, the metal of the shank being slit along lines from a point in proximity to the pivot of the latch upward toward the hook and cut away from the metal of the shank at the upper end to form a leaf spring integrally 25 united at its lower end to the metal of the shank, the free end of the spring extending upwardly and adapted, in the upward movement of the latch, to engage the latch before it contacts with the hook and tending, when the latch is closed against the hook, to open it.

In testimony of which invention, I have hereunto set my hand, at Philadelphia, Pennsylvania, on this 6th day of June, 1927.

HUBERT R. SCHMIDT.
